(57) **CLAIM**

The ornamental design for a tubular grip for a racquet, as shown and described.

DESCRIPTION

FIG. 1 is a perspective view of a preferred embodiment of a tubular grip according to my new design;
FIG. 2 is a front elevational view of the tubular grip of FIG. 1;

FIG. 3 is a rear elevational view of the tubular grip of FIG. 1;

FIG. 4 is a right side elevational view of the tubular grip of FIG. 1;

FIG. 5 is a left side elevational view of the tubular grip of FIG. 1;

FIG. 6 is a top plan view of the tubular grip of FIG. 1; and,
FIG. 7 is a bottom plan view of the tubular grip of FIG. 1.
The broken lines in FIGS. 1-7 represent environment and
are for illustrative purposes only and do not constitute part
of the claimed design.
